(57) **CLAIM**

The ornamental design for a thermocycler, as shown and described.

DESCRIPTION

The patent or application file contains at least one drawing executed in color. Copies of this patent or patent application publication with color drawing(s) will be provided by the Office upon request and payment of the necessary fee.

1. Thermocycler
2. Thermocycler
- 1.1 : Perspective
- 1.2 : Unfolded
- 1.3 : Front
- 1.4 : Front view showing the status light line in green
- 1.5 : Front view with status light line in red
- 1.6 : Right
- 1.7 : Back
- 1.8 : Left
- 1.9 : Top
